DISPLAY CARTON

Eli I. Vranesic, Etobicoke, Ontario, Canada, assignor to
W. R. Grace & Co., Duncan, S.C., a corporation of
Connecticut

Filed Dec. 17, 1964, Ser. No. 419,133
7 Claims. (Cl. 206—45.31)

ABSTRACT OF THE DISCLOSURE

A display carton having a curved transparent display surface provided by shortened top and front panels interconnected by end panels with an arcuate upper edge which may be overwrapped with a heat shrunk thermoplastic film.

This invention relates to a display carton. In one aspect the invention relates to a display carton having an arcuate transparent window.

It is an object of the invention to provide a display carton. Still another object is to produce a package with means to resiliently support the product to reduce breakage.

Yet another object of the invention is to provide a package that may be conveniently and compactly folded when not in use.

Still another object is to provide a display carton particularly suitable for overwrapping with a heat shrinkable film.

These and other objects of the invention will be readily apparent to those skilled in the art from the following disclosure, appended drawing and claims.

The display carton of this invention has a number of advantages over the usual display cartons having an open top. By employing this new carton, a package is provided which has greater rigidity to withstand the shrink forces of a heat shrinkable film, ability to stack, greater product visibility when stacked and better product protection.

FIGURE 1 is a perspective view of the display carton 2 of the invention with a transparent film.

FIGURE 2 is a perspective view of a carton 3 suitable for the construction of a display carton.

FIGURE 1 illustrates one embodiment of the invention for a display carton 2 and includes a bottom panel, back panel, front panel 6 and top panel 12 hinged to each other, in series, along with end panels suitably hinged and locked to provide a carton. Preferably the carton 2 is an elongated hexahedral as illustrated but may also include a variety of shapes and ratios of length, width and heights. Preferably, the top panel and front panel 6 have resilient flaps 14 and 4 hingedly connected thereto which are folded inwardly to provide resilient support for any product contained therein. A suitable product, such as wafer 48, is inserted into the container with the support flaps 14 and 4 firmly supporting the wafers. The front panel 6 and top panel 12 are narrow thus leaving a display area and so as to provide access to the interior of the package when the film 50 is removed. Since the upper edges of the respective end panels are arcuate, this provides, in combination with a heat shrinkable film 50, a curved transparent display surface shaped to closely follow the arcuate contours of the wafer thus improving the overall appearance of the product and package.

FIGURE 2 represents a suitable blank 3 for the construction of the carton and comprises a rectangular blank of cardboard or the like which may be elongated or substantially of equal length and width. The blank 3 is pre-scored (represented by the dotted lines in FIGURE 2) so as to form hinged, connecting, elongated panels comprising, in series, a front flap panel 4, a front panel 6, a bottom panel 8, a back panel 10, a top panel 12, and a top

2

flap panel 14. The top panel 12 is preferably of substantially less width than said bottom panel and said front panel is preferably of substantially less width of said back panel so as to provide a display opening as hereinbefore discussed. End panels 16, 18, 20, 22, 24, 26, 28, and 30, which extend laterally from the ends of the front, bottom, back, and top panels, are pre-scored and thus hingedly connected so that upon being folded together, the panels interlock and provide a closed carton. A first pair of end panels 16 and 18, having one end panel hinged to each end of the front panel but having substantially greater width than said front panel, has arcuate edges extending from an intermediate portion of the upper edge thereof to the point of contact (42 and 40) with the upper edge of said front panel 6. A second pair of end panels 24 and 26 is provided with an end panel hinged to each end of the back panel 10, said end panels 24 and 26 being arcuate from an intermediate portion of the outside edge thereof to an intermediate portion of the bottom edge of said back panel 10. These end panels (connected to the front and back panels) are folded inwardly to enclose the product and are interiorly positioned by interlocking end panels 16, 18 and 24 and 26. A third pair of interlocking panels 20 and 22, which extend laterally from each end of the bottom panel 8, are provided with interlocking slits 36 and 38 extending from the top edge to the center portion of the end panel. A fourth pair of end panels 28 and 30 extends laterally from each end of the top panel with the overall width of the end panels being substantially equal to the combined width of the top panel 12 and top flap panel 14. This fourth pair of end panels has edges arcuate from the intermediate portion of the respective bottom edge to the lowermost point of contact (44 and 46) with the top panel. These end panels 28 and 30 also have slits 34 and 32 so as to provide for interlocking between the respective third and fourth pairs of interlocking end panels. Preferably, a portion of the upper outer quadrant of these interlocking panels is cut away to provide ease of interlocking. A neater package is possible by slashing the top flap 14 at the upper edges to permit the points of contact (44 and 46) to be slightly inward of the edge of the top flap.

Preferably, the resultant carton is overwrapped with a transparent film. Particularly useful as wrappings are the preferred heat shrinkable films, such as the biaxially oriented, irradiated polyethylene films described in patents issued to Baird et al., U.S. 3,022,543 and Rainer et al., U.S. 2,877,500. Any suitable transparent film (including laminates) may be employed including the Sarans (vinylidene chloride and vinylchloride copolymers), polyethylene, polypropylene and the like. Preferably, the film is 0.1 to 20 mils thick.

While certain structures and process steps have been described for purposes of illustration, the invention is not limited to these. Variation and modification within the scope of the disclosure and the claims can readily be effected by those skilled in the art.

I claim:

1. A display carton comprising:
  - (a) a bottom panel,
  - (b) a back panel,
  - (c) a top panel,
  - (d) a front panel,
  - (e) a pair of end panels,
  - (f) said panels hinged to each other so as to form a carton,
  - (g) said front panel extending upwardly from said bottom panel but terminating at an intermediate portion of the front edges of the connecting end panels,
